UNITED STATES PATENT OFFICE.

PAUL NORTH, OF LAKewood, OHIO.

TARGET TRAP.

Application filed October 5, 1922. Serial No. 592,474.

To all whom it may concern:

Be it known that I, PAUL NORTH, a citizen of the United States, residing at Lakewood, in the county of Cuyahoga and State of Ohio, have invented a certain new and useful Improvement in Target Traps, of which the following is a full, clear, and exact description, reference being had to the accompanying drawings.

10 This invention relates to target traps, and has for its general object greatly to increase the range of operation and to improve the efficiency of such apparatus.

As is well known, the ordinary target trap 15 is capable of quick and uninterrupted angular adjustment only in the slightly upwardly-inclined plane in which it ordinarily operates. Its vertical inclination or throwing angle is usually changed only for the 20 purpose of offsetting or compensating for wind direction. If the targets are thrown against or into a strong wind, the effect is to make them climb with reference to the inclined plane of the trap platform, while, 25 if thrown with a strong following wind, the effect will be to make them "duck." Standard traps heretofore in use have been provided with means for varying this inclination of the table or platform, but these adjusting means require the throwing operation to be suspended whenever and until such 30 adjustment is made. With the adjusting means heretofore in use, if it is desired to change the inclination frequently, then only 35 a small fraction of the total number of targets capable of being thrown by the machine or trap can be released during a given period of time. For instance, in tournament shooting, a trap will ordinarily throw about 800 40 targets per hour. With the means heretofore employed for changing the inclination or throwing angle of the trap or platform, if such means should be operated as rapidly as possible after each target-release, then 45 only about 50 targets per hour could be thrown.

With the trap shown and described herein, it is possible, not only to approximate closely the conditions which exist in field shooting, 50 but to do so without any interruption whatsoever of the target-throwing operation. That is to say, the targets may be thrown in the usual manner from the platform, with the usual range of lateral angular variation 55 obtainable between the paths of successive targets, and the platform may be adjusted

at the same time about a substantially horizontal axis, whereby the vertical or throwing angle made by successive targets may be varied, and this change of adjustment is entirely within the control of the operator and can be accomplished without the knowledge of the shooters or contestants.

Other and more limited objects and advantages of the invention will be pointed out hereinafter in the specification.

In the drawings forming a part hereof, Fig. 1 represents a side elevation of a trap constructed in accordance with my invention; Fig. 2 a fore-and-aft sectional detail taken at one side of the center of the apparatus shown in Fig. 1; Fig. 3 is a detail in plan of the sub- and tilting-bases; Fig. 4 a sectional detail corresponding to the line 4-4 of Fig. 3, the central standard being indicated in dot-and-dash lines; Fig. 5 a plan view of the platform, showing the manner of placing targets on the throwing arm; and Fig. 6 a sectional detail corresponding to the line 6-6 of Fig. 5.

In the embodiment of my invention disclosed herein, the throwing portion of the trap, which may be of any approved standard construction, is mounted upon a supporting member, which will be referred to hereinafter as a "tilting base," and this tilting base in turn is mounted upon a second supporting member, which will be referred to hereinafter as a "sub-base." The sub-base will be secured to the foundation and, in the embodiment shown herein, comprises a base plate 1, side plates 2, and a rear plate or wall 3, the side plates extending upwardly at their rear ends and provided each with a boss 4 having a bore therethrough constituting a bearing for a stud shaft on which the tilting base is mounted. Secured to one of the side walls 2 of the sub-base is an arm 5 having its upper portion projected inwardly above the longitudinal central part 100 of the sub-base, as indicated at 5^a, for a purpose to be explained hereinafter.

The tilting base, to which reference has been made hereinbefore, comprises generally a bottom or base plate 6, having its central portion open, for lightness of construction, and provided with short side plates 7 and a short rear plate or wall 8. The side plates extend rearwardly and upwardly, as indicated at 7^a, and each is provided with a boss 9, said bosses being provided with bores adapted to register with the bores in the

bosses 4 and to receive jointly therewith the studs 10. The sides 6^a of the front portion of the bottom plate 6 are faced off and fit fairly closely between faced-off projections 5 2^a on the sides of the sub base. The tilting base is shown herein as provided with a central standard 11, which may be fastened to the bottom plate 6 of the tilting base, as by means of bolts 12.

10 The construction shown and described herein dispenses with the necessity for any pivotal connection between the platform and the part or tilting base by which it is supported. However, in order to adapt my invention to existing traps having standards 11, the frame 13 may be provided with a downwardly projecting extension 13^a which can be pivotally connected to the standard by the bolt 14. The standard 11, frame 13, 20 extension 13^a and bolt 14 are the means usually employed in standard traps for varying the throwing angle or inclination of the table or platform about a horizontal axis; but, in order to effect this variation, it is 25 necessary to suspend the operation of the trap, slack off the clamping bolt 14, adjust the platform to its desired position, and set up again on the bolt. As pointed out heretofore, there is no necessity for a pivotal 30 connection between the frame and the tilting base. The standard 11 and extension 13^a may, however, be employed for the application of existing traps to the tilting base, but without the necessity for slackening off and 35 setting up on the bolt 14.

The complete target-supporting and throwing mechanism carried by and including the frame 13 are preferably of the type shown in the application of Robert S. Elliott, Serial No. 494,815, filed August 24, 1921. In the drawing, 15 denotes the platform or table, 16 the throwing arm, 17 the throwing spring, 18 the resetting spring, 19 an arm pivoted at its upper end and having 40 its lower end provided with a pin 20 on which the link 21 is mounted, the said link being connected at one end to the throwing spring and at its other end to the pull rod 22, the parts being of the usual and ordinary construction. The spring 17 is of such 45 length and the pivot 19^a for the arm 19 is so located that, when the spring 17 is not under throwing tension, the lower end of the arm 19 is substantially coincident with the axis of rotation of the tilting bore. With this 50 arrangement, the adjustment of the tilting bore about its horizontal axis will cause no material variation in the length of the spring 17; hence such adjustment will not vary the 55 throwing tension of said spring, the arm 22 being pulled rearwardly the same distance each time the trap is operated to throw a target.

For the purpose of operating the tilting base, I prefer to employ the detailed mecha-

nism shown in the drawings, said mechanism comprising a rotary shaft 23 having a worm 24 thereon meshing with a worm gear 25 on a shaft 26 extending transversely of and mounted on the front of the sub-base, the shaft 26 being provided with a pinion 27 meshing with a rack segment 28 secured to the front of the bottom plate 6 of the tilting frame. The shaft 23 may be supported conveniently in journals 23^a on one of the sides of the sub-base and is provided with an operating handle 23^b, while the shaft 26 may be conveniently supported in suitable bearings 26^a provided in bosses at the front ends of the sides 2 of the sub-base. The rack 28 may be formed separately from the bottom plate of the tilting base and may be secured to the latter, as shown in Fig. 2; that is to say, by means of a plate 29 extending beneath the front of the plate 6 and bolted thereto, as indicated at 30. For the purpose of assisting the operation of elevating the target-supporting and throwing portion of the trap, a spring 31 is supported at one end from the upper end 5^a of the arm 5 and is 90 connected at its other end to the rack 28. This spring tends to elevate the front end of the tilting base and thus assist the operator in quickly elevating the lower front end of such base.

By using a slow pitch for the worm 24 and worm gear 25, the worm and worm gear constitute a self-locking means whereby the trap may be supported in any position to which it may be adjusted and without the 100 liability to "run down" by reason of the weight of the parts operating upon the pinion 27 and shaft 26.

In the type of platform and throwing arm shown in the Elliott application referred to hereinbefore and illustrated more particularly in Figs. 5 and 6 hereof, variations in the nearly horizontal angle at which a target is discharged from the platform are accomplished by varying the positions of the targets on the throwing arm. By reference to the drawing it will be seen that, when the arm 16 is in its throwing position, two targets 31 may be placed in contact with said arm, between the stops 32 and 33 on the platform; or a single target may be adjusted to any desired position along the said arm between said stops. By this variation in the position of a single target, a corresponding variation in the direction of flight from the platform is obtainable. By using this construction of platform and arm, and with power-operated means such as set forth hereinbefore for rocking the platform about the horizontal axis of the studs 10, it is possible for a single operator to vary at will the vertical or throwing angle of the platform 15 without apprising the contestants of such change and without interference with the simultaneous variation of the ordinary

nary throwing angle or line-of-flight of the target.

Having thus described my invention, what I claim is:

- 5 1. In a target trap, the combination of a sub-base, a tilting base adjustably mounted upon the sub-base, a complete target throwing mechanism mounted upon the tilting base and comprising a frame additional to such tilting base, and power-operated means for moving the tilting base upon the sub-base and without interruption of the target-throwing operation.
- 10 2. In a target trap, the combination of a

support, a platform mounted on said support upon a substantially horizontal pivot, a pull rod, a throwing spring, and an arm pivotally supported by said platform and connected at its swinging end with said spring, the arm-supporting pivot being so arranged and the spring being of such length that, when the latter is in its released position, the lower end of such arm will be substantially coincident with such platform pivot.

In testimony whereof, I hereunto affix my signature.

PAUL NORTH.
